(Cl. D4—3)

To all whom it may concern:

Be it known that I, Jack L. Day, a citizen of the United States, residing at Oakland, in the county of Alameda and State of California, have invented a new, original, and ornamental Design for a Tooth Brush and Tumbler Holder, of which the following is a specification, reference being had to the accompanying drawing, forming part thereof.

Fig. 1 is a perspective view of a toothbrush and tumbler holder, showing my new design;

Fig. 2 is a top elevational view;

Fig. 3 is a front elevational view;

Fig. 4 is a side elevational view; and

Fig. 5 is a bottom elevational view thereof.

I claim:

The ornamental design for a toothbrush and tumbler holder, substantially as shown.
